UNITED STATES PATENT OFFICE.

FRANK D. BARTLETT, OF BOSTON, MASSACHUSETTS.

MACHINE FOR FORMING PULLEY-BLOCK STRAPS.

SPECIFICATION forming part of Letters Patent No. 268,982, dated December 12, 1882.

Application filed December 7, 1881. (Model.)

To all whom it may concern:

Be it known that I, FRANK D. BARTLETT, a citizen of the United States, residing at Boston, county of Suffolk, and State of Massachusetts, have invented new and useful Improvements in Machines for Forming Pulley-Block Straps, &c., of which the following is a specification.

My invention relates to improvements in machines for forming pulley-block straps, and the particular matter which constitutes my improvement will be hereinafter particularly described and made the subject of specific claims.

Referring to the accompanying drawings, Figure 1 represents a top view of the machine, showing the several operating parts in the positions they occupy at the commencement of the operation of forming the strap; Fig. 2, a similar view showing the forming parts only in the positions they occupy when the strap is partially formed; Fig. 3, a similar view showing the forming parts only in the positions they occupy when the strap is completed; Fig. 4, a vertical longitudinal section, the parts being in the positions shown in Fig. 1; Fig. 5, a similar sectional view, the parts being in the positions shown in Fig. 2; Fig. 6, a vertical transverse section, the parts being in the positions shown in Fig. 1; Fig. 7, a similar sectional view, the parts being in the positions shown in Fig. 3; Fig. 8, a similar sectional view taken on the line xx of Fig. 1, the parts being in the positions shown in Fig. 3; and Fig. 9, a vertical longitudinal section, showing the forming device in position to allow of the removal of the formed strap.

A suitable frame supports a cast-iron bed-plate, A, upon which the several operating parts are arranged. The die-forming parts are arranged at one end of the bed-plate and the operating connections at the other.

It will be understood that the formed strap a , Fig. 9, is bent with its ends a' , Fig. 3, parallel to each other, the bend having the form of the block, and in cross-section is of a concavo-convex shape, to suit the groove around the block.

A die, M^2 , is detachably secured to the bed-plate A, with its die part a^2 proper of semicircular recessed form and in cross-section the

counterpart of the outer concave side of the formed strap. This die gives the bend to the strap and the concavo-convex form to the bent part, in connection with a "former," M, having the counterpart in cross-section of the die. The former is mounted upon a short slide, L, fitted to be moved in a longitudinal groove or slot, K, in the bed-plate toward and from the die, into the recess in which the former is driven with the strap to give it the form stated.

The former is composed of two cavitto-molded sections, m m' , mounted upon a vertical stem, L', fixed to the short slide L, the upper section, m , of said former being movable, for a purpose to be presently stated. These sections m m' are placed upon the stem L', so that their smaller ends will join, the profile of the sections so joined being the counterpart in cross-section of the die and of the formed strap. These former parts are also detachably secured to the stem. Dies Q, arranged to slide in guides at right angles to and adjacent to the recessed face of the fixed die M^2 , and on each side of the longitudinal slot K in the bed-plate, are adapted to be moved toward each other and against the sides of the strap to complete the bend and concavo-convex form thereof when the former is driven into the fixed die. For this purpose these sliding dies are formed at c c in cross-section the counterpart of the former and of the fixed die, and with flat faces c' c' , to give the proper parallel relation to the ends a' of the strap while completing its form, as shown in Figs. 3 and 8.

A driver-bar, J, arranged in the longitudinal groove K of the bed-plate, is adapted to strike and drive the former and the strap to be formed into and upon the fixed die, and for this purpose the end of the driver is made to fit and have a bearing upon the joined sections of the former.

On each side of the longitudinal slot K, and out of the range of the movement of the sliding dies and of the former, are secured in the bed-plate pins or studs b b , against which the strap is placed edgewise upon the bed-plate, and by which it is held in proper position across the path of the former to be struck and carried forward by it. These studs are provided with caps or T-heads b' , beneath which

the strap is placed with its flat side against the studs, across the slot, and behind the former, and the ends of the strap are thus supported as the former strikes and carries it 5 against the die, as shown in Fig. 1.

The driver-bar J and the sliding dies Q may be operated by any suitable mechanism. That shown gives the advantage of placing the control of the forming parts under the operator.

- 10 A crank-shaft, B, is mounted in suitable bearings upon the bed-plate, and operates at will the driver-bar which operates the forming device. That part of the driver-bar which strikes and forces the former and the strap 15 into the die is narrow and placed edgewise in central relation to the former, and of a height above the bed-plate about equal to the width of the strap being formed. The other end of the driver-bar has a cross-head, J', fitted to 20 move in guides J² on the bed-plate, and having a top recess or cavity, B², while a pitman-rod, I, on the crank G is carried by a cross-head, A², having a projection or tenon, a³, in such relation to and above the driver-bar cross- 25 head that the tenon of the pitman cross-head will, when depressed, enter the cavity B², and thus connect the pitman-rod with the driver-bar to impart to the latter a reciprocating motion.

- 30 The cross-head of the pitman is carried in ways I², mounted upon springs a⁴ a⁴, which constantly exert their force to effect and maintain the disconnection of the pitman-rod from the driver-bar, as in Fig. 4, in order that the latter may remain inoperative while the strap 35 is being placed in position for operation, and to allow of the removal of the formed strap without interfering with the continuous motion of the crank-shaft.

- 40 The connection of the pitman-rod with the driver-bar to operate the latter may be made by a hand-lever pivoted to the bed-plate and arranged across and upon the yielding ways I², with its handle in position to be controlled 45 by the workman. As shown, however, such connection is effected by a treadle, R, or hand-lever pivoted to the frame beneath the bed-plate and connected by vertical rods R' with the yielding ways I², which carry the pitman 50 cross-head connecting-tenon.

- The side dies, Q, are operated by side crank-shafts, E E, mounted in bearings on the bed-plate, and said dies may be controlled in their operation by the workman or adapted for uninterrupted operation, as may be desired. As shown, these side dies have no fixed connection with their operating crank-shafts; but rods N N, operated by cranks H H, are adapted to be connected with said side dies and reciprocate them simultaneously and at the proper time. Such connection and disconnection is effected in a manner similar to the pitman-rod and driver-bar connection. For this purpose the free ends of the rods N N are supported 65 and carried by yielding ways N' N', and have tenons or projections n, adapted to be de-

pressed simultaneously each into a cavity, n', in the upper surface of said die-blocks by means of a treadle, P, or hand-lever, pivoted to the under side of the frame and connected to said yielding ways N' by vertical rods P', so that the depression of the treadle or hand-lever at once connects the rods N N with the said dies and causes them to be reciprocated, and upon the release of the treadle such connection is interrupted. When adapted for uninterrupted operation the rods N N have fixed connection with the dies in any suitable manner.

The slides of the forming device and of the 80 driver-bar are fitted within the slot K, so as to move freely upon tongue-and-groove connections, so that these parts cannot be displaced under the force exerted by the crank upon the driver-bar.

85 The side shafts, E E, are operated by bevel-gear F F meshing with the bevel-gear D D on the crank-shaft, which is driven by a belt or belts leading from the pulleys C C to any suitable power. Balance-wheels are mounted on 90 the crank-shaft B, if desired.

95 It will be understood that the extent of the movement of the driver-bar is equal to the throw of the crank G, and just sufficient to give the required pressure to form the strap over the die, the former in such operation serving as the matrix for the dies.

100 It will also be understood that the throw of the cranks H H is just sufficient to give the required pressure to the side dies to complete the formation of the strap around the former.

The forming device proper is composed of the sections m m', the slide L, and the stem L', and the upper section, m, is adapted by any suitable means to be held firmly upon the 105 base-section during the operation of forming the strap, and may be removed from its holding-stem to allow the work to be removed. The upper section, as shown, is adapted for vertical movements upon the stem L', and a 110 cam-lever, S, pivoted to the stem, serves, when depressed, to hold the upper section, m, firmly upon the base-section against the force exerted by the dies and the driver-bar in forming the strap. Springs d connect the upper section to 115 a cross-arm, e, of the stem L, so that when the cam-lever S is raised from its holding position these springs lift the upper former-section, m, and hold it sufficiently above the base-section, as shown in Fig. 9, to free the formed 120 strap and allow it to be removed, the forming device, with the strap, being first moved away from the dies.

125 The slides which carry the driver-bar and the forming device are not connected, leaving the latter free to be moved out of the die by hand as soon as the side dies have been withdrawn from the forming device.

130 The former-sections and the dies are adapted for removal and replacement by others for different sizes of straps and for different kinds of work, such as chain-links, thimbles, and

different forms of straps for single pulley-blocks and for reefing pulley-blocks.

The iron to be wrought into the straps is first cut to the necessary length and punched 5 at the ends. The strap, being heated to a red heat, is placed edgewise, as in Fig. 1, upon the bed-plate, behind the former and against the studs b b , the T heads b' of which serve to hold the ends of the strap in proper position when 10 struck by the former, which is driven against the strap, and the latter in turn is driven against the fixed die and is bent over the former and given the desired form by the force and pressure of the driver-bar. The action of the 15 fixed die is immediately succeeded by the action of the side dies, which are caused to advance toward each other, being properly timed for the purpose, and press the ends of the strap inward around the former to complete the bend 20 and form of the strap. In this operation of the side dies their flat faces press the ends of the strap against the opposite sides of the driver-bar and leave its punched ends in parallel positions, as shown in Fig. 3. The return movements 25 of the driver-bar and of the side dies leave the forming device in position to be moved by hand away from the dies, and upon the release of the holding device of the upper section of the former it is or may be freed from 30 the formed strap, leaving it free to be pushed or drawn from the former, in readiness to be put around the block.

The treadle and hand-lever are arranged so that the workman may from the forming end 35 of the machine control the movements of the side dies and of the driver-bar, as stated.

As the strap must have the exact form of the block, it will be noticed that the dies and the former are adapted to give such form, and 40 that for this purpose the corners of the sliding dies form a continuation of the fixed recessed die part when the dies are closed upon the strap, leaving its ends straight, by which to properly secure the strap upon the block.

45 The fixed die is secured in a suitable housing in the bed-plate, and the adaptation for the removal and replacement of the forming parts by others of different sizes or form increases the working capacity of the machine.

50 For single blocks the strap will be formed round at the top, as shown; but in double and treble blocks the top of the second strap is somewhat oval. This is also true of the third strap where there are three blocks.

For making chain-links and thimbles the 55 former and the dies would be varied.

I am aware of the Patent No. 264,268, dated September 12, 1882, for machine for forming pulley-block straps, and my claim is not intended to cover the machine described and 60 shown in said patent, but the improvement thereon, which consists of a combination of elements embracing the pitman-rod adapted for connection and disconnection with the sliding driver-bar which operates the forming 65 device, the side crank-shafts and their pitman-rods, yielding guides for the latter, and suitable gearing for connecting the said crank-shafts for operation in connection with the sliding driver-bar, the forming device, and the 70 fixed and sliding dies.

The specific construction by which the connection and disconnection of the several pitman-rods, with their operating parts, is effected under the control of treadle and spring connecting guides for said pitman-rods also forms 75 part of my improvements, which matter is specifically presented in the following claims.

I claim—

1. The combination of the fixed die M^2 , the 80 sliding side dies, Q Q , the sliding driver-bar J , having a top rib, and the forming device, with the crank-shaft B , the pitman-rod I , adapted for connection and disconnection with the driver-bar head, the side crank-shafts, E E , 85 their pitman-rods N N , the yielding guides N' for said pitman-rods, and suitable gearing for connecting the said crank-shafts, substantially as described, for the purpose specified.

2. In combination, the fixed die M^2 , the sliding 90 side dies, Q Q , the sliding driver-bar J , having the recessed cross-head B^2 , the independent sliding forming device interposed between said fixed die and said driver-bar, the crank-shaft B , the pitman-rod I , having the 95 tenon a^3 , the cross-head A^2 , the guides l^2 , the springs a^4 , and the treadle P , all constructed and arranged for operation as described, for the purpose specified.

In testimony whereof I have hereunto set my 100 hand in the presence of two subscribing witnesses.

FRANK D. BARTLETT.
